Inventor:
Sigmund Loewe

UNITED STATES PATENT OFFICE

SIEGMUND LOEWE, OF BERLIN, GERMANY, ASSIGNOR TO RADIO CORPORATION OF AMERICA, A CORPORATION OF DELAWARE

WIRELESS RECEIVING SET FOR COMPENSATING DISTURBANCES

Application filed July 27, 1926, Serial No. 125,313, and in Germany August 1, 1925.

This invention relates to wireless receiving sets, and has particularly for its object to suppress the disturbances which are especially caused by electrostatic conditions.

5 By careful investigations I have found that these disturbances may be fully suppressed in the following manner:

The receiving aerial is carried in series or parallel connection through two similar receiving sets E_1 and E_2 . These receiving sets may be of any desired construction, and may, for instance, consist of a three-valve reflex set. One of these sets, for instance E_1 , is sharply tuned to the wave to be received and 10 generally so adjusted, that the reception will be as good as possible. The reception will in this case comprise to a great extent atmospheric and other disturbances, which are mixed with the reception. The second receiving set is sharply tuned to a wave, which is not very different from the wave, to which the other set is adjusted. This second receiving set, being out of tune with respect to the wave to be received, will not be acted 15 upon by the latter. The disturbances, however, will be received by said second receiving set in equal strength and phase. If the reception be designated with E and the disturbances with S , the first receiving set will 20 reproduce in a telephone or loudspeaker the sum of the reception and the disturbances, that is E plus S , while the second receiving set will solely reproduce the disturbance, that is S . The difficulty now consists, to solely 25 reproduce the difference of the two energies received by the two receiving sets that is the quantity $E = (E + S) - S$.

In the accompanying drawing I have represented a wireless receiving set according to my invention. Fig. 1 is a wiring diagram showing diagrammatically the connections of the wireless receiving set according to my present invention. Figs. 2 and 3 are wiring diagrams showing connections for 40 modified wireless receiving sets according to my invention.

According to the connections shown in Fig. 1 the operation is as follows:

Instead of the telephone or loudspeaker, 45 a resistance for alternating current, that is a

choke coil or a resistance having a high-resistance value such as D_1 and D_2 is inserted into the circuit of each receiving set. Paralleling these resistances D_1 and D_2 there are arranged metallic plates F_1 , F_2 and F_3 , F_4 respectively, said metallic plates representing electrical capacities. Intermediate these capacities, further capacity plates F_6 and F_7 , respectively are provided. Between the capacity plates F_6 and F_7 , the controlling circuit of a tube amplifier V is inserted, said amplifier being for instance arranged to operate in the known capacity-resistance connection. In Fig. 1 a double amplifier is shown diagrammatically. In order to explain the 55 operation of this device, it is, for instance, assumed, that the lower ends of the resistances D_1 , and D_2 , and therewith also the plates F_2 and F_4 are grounded. The plates F_1 and F_2 , therefore, are under the action of 60 potential variations against ground, and more particularly the potential variations of the plate F_1 will take place according to the sum E plus S , while the plate F_3 will solely be under the action of potential variations 65 according to the quantity S . The plates F_6 and F_7 now may be adjusted relatively to the plates F_1 , F_2 , F_3 and F_4 in such a manner, 70 that a complete compensation of the disturbances will take place. Between the plates 75 F_6 and F_7 , a very high resistance may be inserted in order to avoid constant charges of the grid.

The combination may also be carried out in the manner of providing a bridge connection 80 for the tubes, such as is shown in Fig. 2. In this case two tubes R_1 and R_2 having common or separate heating and anode batteries are connected to a transformer with three windings a , b and c , the coupling between said 85 windings being made adjustable. The grid of tube R_1 is connected to the plate F_6 and the grid of tube R_2 to the plate F_7 , said plates 90 F_6 and F_7 , being adjustably arranged within corresponding capacity plates, as in Fig. 1. The indicator is connected to the winding b , 95 the cathodes of the tubes R_1 and R_2 are grounded and connected to the plates F_6 and F_7 , by means of high leak resistances K . Instead of the indicator, also a multiple valve 100

amplifier may be inserted into the winding *b*. It is obvious, that in the manner described, the grids of the tubes R_1 and R_2 will be acted upon by the receiving set E_1 , according to the value *e* plus *s*; and by the receiving set E_2 according to the value of *S*, and more particularly to an extent, which may be independently regulated by adjusting the plates F_1 , F_2 , F_3 and F_4 . One will therefore be enabled to cause only the difference of these two values to act upon the winding *b*, this being effected by the direction in which the windings *a* and *b* are wound. In some cases also the insertion of a coupling transformer having three windings *a*, *b* and *c*, as indicated in Fig. 3, will give the same result; in this case the winding *a* is directly connected to the receiving set E_1 and the winding *c* directly to the receiving set E_2 and more particularly in such a sense, that the winding *b* will be acted upon solely by the difference of the actions of the two receiving sets.

I claim:

1. A wireless receiving system for eliminating disturbances comprising two receiving circuits one of said receiving circuits being tuned to the wave to be received, the other of said receiving circuits being tuned to a wave somewhat different from said former wave, whereby said first circuit will receive said former wave and the disturbances and said second circuit only the disturbances, and connections for the audio outputs of said circuit for balancing capacitively the disturbances received by said first circuit against the disturbances received by said second circuit so as to obtain a combined receiving action of said circuits without said disturbances.

2. A wireless receiving system comprising two receivers, one of said receivers tuned to receive a desired signal and incidentally receiving undesired impulses, the other of said receivers being detuned with reference to said desired signal but receiving said undesired impulses, an adjustable capacity in each of the audio frequency output circuits of said receivers, an electron emission tube amplifier including a grid and filament, a connection from the grid of said amplifier to one of said capacities and a connection from the filament of said amplifier to the other of said capacities whereby solely desired signal impulses affects the thermionic stream of said amplifier.

3. A wireless receiving system for eliminating undesirable disturbances comprising a plurality of receiving circuits, one of said circuits being tuned to a desired signal frequency, another of said circuits being detuned relative to said desired frequency whereby said first circuit will receive said signal and the disturbances and said second circuit only the disturbances, and grounded means connected to each circuit audio output to balance capacitively the disturbances received by said first

circuit against the disturbances received by said second circuit.

In testimony whereof I have affixed my signature.

SIEGMUND LOEWE.
